UNITED STATES PATENT OFFICE.

JOHN EDWARD THORNTON, OF WEST HAMPSTEAD, LONDON, ENGLAND.

CINEMATOGRAPH FILM MATERIAL.

Original application filed May 5, 1924, Serial No. 711,255, and in Great Britain May 18, 1923. Divided and this application filed October 31, 1925. Serial No. 66,050:

This invention relates to film material for the production of transparent multi-color cinematograph film-positives in four or three colors.

5 In the specification of my U. S. application Serial No. 711,255, filed May 5, 1924, of which this application is a division, I have described a four-color cinematograph film-positive built up from four differently-colored component images, which are formed in 10 four differently-colored colloid layers, a separate color upon each side of two strips of thin celluloid support; the two strips with their four images being cemented together after printing and finishing, to form 15 a single compound film-strip of four-color pictures which are produced by the superimposition and combination of the four component images within the space of one picture-area, the assembled complete picture comprising one image on the front, two in the centre, and one on the back of the film.

In the specification of my U. S. application Serial No. 60,348, filed October 3, 1925, 25 I have described a form of film-material comprising a double-width support of celluloid, with two parallel stripes of colored colloid attached to the front and two on the back of the support, all four stripes being of 30 different colors, and also with a layer of soluble removable light-obstructing material placed between the colored stripes in order that the two sides of the sensitive film can be simultaneously printed without the light 35 from one side penetrating to and spoiling the print on the other side.

In the present invention a film-material similar to the above is provided but with the difference that the light-obstructing layer is omitted, so that the light can penetrate 40 in order to form two prints by the method hereinafter described.

In the specification of my U. S. application Serial No. 60,349, filed October 3, 1925, 45 I have described methods of manufacture equally applicable to both kinds of film-material described in the application Serial No. 60,348, filed October 3, 1925, and in the present application.

50 This invention therefore consists of a ready-colored film-material (either ready-sensitized or adapted to be sensitized by the user) comprising a strip of celluloid or other waterproof material of double standard width and half standard thickness and a

layer of colored colloid in two differently-colored stripes on both sides of the celluloid support, making four colloid stripes and four colors altogether without a light obstructing dye between the film-material and the layers of colloid.

55 This film-material is intended for use in printing from color-screen negatives of the type described in my concurrent application Serial No. 711,254, filed May 5, 1924, and British Patents Nos. 233,989, dated February 15, 1924, 224,571, dated May 18, 1923, and 224,572, dated March 18, 1923, in which the colors are interspersed as they are in the well-known "autochrome plate," and printing is effected by using only the one negative by printing from only one side of the film, by making two successive exposures, through differently-colored light filters, so that only one color-component of the negative is printed on the sensitized front at one exposure and the other color printed on the sensitized back (through the front sensitized layer and its "cut-out" filters) at the other exposure.

60 In this case therefore one of the color prints is formed upon the front of the film in dots or lines, and the other color-print is formed upon the back of the film in dots or lines that fall in the spaces between those formed upon the other side of the film.

65 The invention will be described with reference to the accompanying drawing wherein:

70 Fig. 1 is a perspective view of a film embodying the invention; and

75 Fig. 2 is a cross-section of the film shown in Fig. 1, transversely of the length of the film.

80 The film-material is manufactured with a transparent central base of celluloid (or similar waterproof material) of only about .00100 inch thick, and of double standard width so that all the four section-images can be printed, developed, and dried simultaneously to secure uniform density and color balance in all images and also to ensure uniform expansion and contraction. When the double-width print is finished and dried it is slit into two separate strips. The colored colloid consists of gelatine, albumen, fish-glue or the like with which suitable dyes or other coloring matter is incorporated.

85 To both sides of the thin double width material an adhesive substratum of the usual

type is applied, of about .00005 inch in thickness (though it may be thinner) and upon this both sides are coated with a layer of colored colloid, arranged as two parallel 5 stripes of different colors upon each side (four stripes in all) which run longitudinally of the film. These layers are preferably made about .00090 inch thick each, but may be slightly more or less. The adhesive substratum serves to indissolubly 10 unite the colored colloid stripes to the central transparent waterproof base.

The colored layers require to be sensitive 15 to light, and may be sensitized by various processes, for example:—

In one method the colored film may be stored in a non-sensitive condition and is rendered sensitive by the printer immediately before use by treatment in a bath of a 20 suitable bichromate salt and then drying. When such film is exposed under a negative or positive the colloid is rendered insoluble in parts, and at those points the coloring matter is permanently locked up with the 25 insoluble colloid, thus forming the image, whilst at other points, it remains free and can be washed out or removed.

In another method suitable salts of iron 30 may be substituted for the bichromate salts, as used in several well-known printing processes.

In another method the colored colloid is sensitized with salts of silver. These may be applied as a bath in the same way as the 35 salts of bichromate or iron, as used in well-known print-out processes.

In another method the film-material is sensitized by the film-maker and can be kept stored for a long period in its sensitive condition and is always ready for immediate 40 use by the printer. In this case the colored colloid and silver salts are formed into an emulsion, as in the well-known gelatino-silver-bromide or gelatino-silver chloride 45 printing processes.

In whichever of these methods is adopted for rendering the colored colloid sensitive to light, the necessary coloring matter is incorporated with the colloid at the time of 50 manufacturing the film, and the coloring matter not required in the image is washed out or removed from the colloid by suitable re-agents after printing and developing.

The coloring matter used in forming the 55 image itself can be rendered still more permanently fixed by the application of suitable mordants, all in manner well-known.

The methods of printing a film sensitized according to any of the different sensitizing 60 processes, and the different treatment required in the developing, and other processes after printing, are all well-known to those acquainted with each process; they 65 form no part of the present invention and are therefore not described in detail herein.

For a four-color film the colors preferred are crimson-red, blue-green, orange-yellow, and blue-violet, but these colors may be slightly modified if desired.

The colored colloid is applied to the 70 double-width strip of transparent waterproof base or support in the form of two parallel stripes of two different colors upon one side of the support and two parallel stripes of two other colors upon the other 75 side of the support.

The film-material is intended for its front prints to be made direct on to its front colored stripes, and the back prints to be made indirectly upon its back colored stripes, by 80 exposing the back stripes through the front ones and through suitable cut-out color filters. By this means prints are made from one double-width negative which comprises four color component images of the screen-filter type as described in my British Patents Nos. 233,989, dated February 15, 1924, 224,571, dated May 18, 1923, and 224,572, dated May 18, 1923, by two exposures alternately through the one negative; the first 85 exposure printing the colored stripes on the back of the film through the colored stripes on the front and through filters which cut out the other color and protect from exposure the front layer whilst the back layer 90 is being printed; after which the front layer is printed at the second exposure with the cut-out filters removed.

It is therefore preferred to place the red and green colored colloid stripes back to back and the yellow and violet back to back, so that the front and back colored stripes are sufficiently nearly complementary to each other to allow of printing through in the manner described. 100

With a double-width sensitized film constructed as described, and a pair of suitable double-width negatives of the type described, all four images can be printed simultaneously and automatically at one 110 printing operation without the necessity of a large amount of highly skilled labour, and the various subsequent operations of developing, fixing, washing, mordanting, color-removing, or the like can also be effected by 115 automatic machinery that will ensure equal treatment of all four sections of the same picture.

Moreover the use of ready-colored film-material made according to this invention 120 obviates the uncertainty of result and great expense in adjusting the colors which would be necessary if non-colored sensitized film were used and the four images colored after development by the known processes of dyeing for each color separately. Also a more certain quality of result is obtained, owing to the coloring matter for each section being incorporated with the sensitized layer at the time of its manufacture in exact 125 130

and carefully adjusted amounts that will give correct color-balance in the finished multi-color picture.

Although primarily intended for the production of cinematograph positive pictures the invention is not restricted thereto but will be found equally applicable to and is intended to be used in other multi-color photography (non-cinematograph).

10 Although the complete film is herein described as a double-width strip, it may for convenience and economy in manufacture be formed as a wide web of several strips, as usual in manufacturing most sensitized material, the web being slit into a number of double-width strips afterwards.

15 Although the coloring matter can be incorporated with the colloid mixture before the film support is coated as strips, I prefer 20 the following method of manufacture.

25 The wide web, or alternatively the double-width strip, is first covered all over upon both sides by a suitable coating machine with non-colored colloid, either of the ready-sensitized or non-sensitized variety. After 30 drying it is next passed through a machine which applies the solutions of coloring matter or dyes in the form of colored strips each being the width of a single film. These solutions 35 are each adjusted to the correct strength or intensity of color and are applied until the colloid is charged to saturation and the colors have penetrated the entire thickness of colloid down to the waterproof base or support.

35 If necessary the colors may be mixed with a mordant; or the mordant may be incorporated with the colloid before the colors are applied; or the mordant may be applied last of all, after coloring.

40 The web or strip is dried and is then ready for use.

What I claim as my invention and desire to protect by Letters Patent is:—

45 1. For the production of multi-color pictures in which four images of different colors are formed upon a single transparent support of double width by printing alternately upon the two sides by two separate succeeding exposures, then developing, finishing, severing into two parts and subsequently superimposing and cementing the two parts; a multi-color cinematograph or other positive film-material, comprising a strip of transparent waterproof support of double width and half thickness, a first layer of colored colloid in two parallel differently-colored stripes upon one side of the support and a second layer of colored colloid in two parallel 55 differently-colored stripes upon the other side of the support, and an adhesive substratum layer between each colloid layer and

its support without a light obstructing layer.

2. For the production of multi-color pictures in which four images of different colors are formed upon a single transparent support of double width by printing alternately upon the two sides by two separate succeeding exposures, then developing, finishing, severing into two parts and subsequently superimposing and cementing the two parts; a multi-color cinematograph or other positive film-material, comprising a strip of transparent waterproof support of double width and half thickness, a first layer of colored colloid in two parallel differently-colored stripes upon one side of the support and a second layer of colored colloid in two parallel differently-colored stripes upon the other side of the support, the colored colloid layers being sensitized, and an adhesive substratum layer between each colloid layer and its support without a light obstructing layer.

3. For the production of multi-color pictures in which four images of different colors are formed upon a single transparent support of double width by printing alternately upon the two sides by two separate succeeding exposures, then developing, finishing, severing into two parts and subsequently superimposing and cementing the two parts; a multi-color cinematograph or other positive film-material comprising a strip of waterproof support approximately .00100 inch thick; a layer of adhesive substratum approximately .00005 inch thick applied to each side of the support; a layer of sensitized colored colloid approximately .00090 inch thick in two stripes on each substratum layer but without a light obstructing layer, the two stripes of colloid on one side of said support being colored differently from those on the opposite side of said support.

4. For the production of multi-color pictures in which four images of different colors are formed upon a single transparent support of double width by printing alternately upon the two sides by two separate succeeding exposures, then developing, finishing, severing into two parts and subsequently superimposing and cementing the two parts; a multi-color cinematograph or other positive film-material of double width comprising a central waterproof support having two differently-colored parallel stripes of sensitized colloid on each side thereof but without a light obstructing layer, the two stripes of colloid on one side of said support being colored differently from those on the opposite side of said support.

In testimony whereof I have hereunto set my hand.

JOHN EDWARD THORNTON.
